(57) **CLAIM**

The ornamental design for a trailer mounted solar powered work lighting system, as shown and described.

DESCRIPTION

FIG. 1 is a top front perspective view of a trailer mounted solar powered work lighting system showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a bottom plan view thereof;

FIG. 7 is a top plan view thereof; and,

FIG. 8 is a bottom front perspective view thereof.

The broken line showing trailer wheels is included for the purpose of illustrating environmental structure and forms no part of the claimed design.
